UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF NEW YORK.

LAMP-MOUNTING.

1,227,258.

Specification of Letters Patent. Patented May 22, 1917.

Application filed November 27, 1916. Serial No. 133,570.

To all whom it may concern:

Be it known that I, CHARLES E. GODLEY, a citizen of the United States, and residing at Detroit, in the county of Wayne and State of Michigan, have invented a new and Improved Lamp-Mounting, of which the following is a specification.

This invention relates to means for securing lamps to upright posts or supports or to supports which lie in vertical planes parallel to the axis of the projected light beam of the lamp, and its object is to provide a support which will permit the lamp to be tilted so as to swing the light beam up or down in a vertical plane while preventing it from swinging in a horizontal plane.

This invention consists, in combination with a lamp and an upright post, of a clamp engaging the post, and a knob on the lamp engaged by the clamp, said knob and clamp being so constructed that the knob can revolve within the clamp on only one axis.

In the accompanying drawing, Figure 1 is a front elevation of a lamp secured to one of the upright supports of a windshield. Fig. 2 is a plan of the clamp and of a knob on the lamp body. Fig. 3 is a section of the clamp on the line 3-3 of Fig. 2. Fig. 4 shows a modified form of clamp and supporting knob.

Similar reference characters refer to like parts throughout the several views.

Many automobiles and other vehicles are not supplied with auxiliary oil lamps and it is often desirable to equip these vehicles therewith. The upright supports of the windshield have been found very convenient for this purpose and lamps have been connected thereto by means of ball and socket joints. This type of support is liable to

permit the lamp to swing down unless made so tight as to render the joint ineffective.

In the present construction, the support 4 of the windshield 5 is engaged by the two clamping members 6 and 7 which are provided with transverse ribs 8 to prevent the clamp from swinging down. A bolt 9 having a nut 10 may be employed to force the members 6 and 7 toward each other.

Extending laterally from the lamp 12 and preferably in a horizontal line passing

through the center of gravity of the lamp is a short post 13 having a plate 14 at one end whereby it is secured to the lamp body, and a knob 15 at its outer end. This knob 55 is not spherical but of some other shape that permits the knob to turn on only one axis. In Figs. 2 and 3 the knob is shown to be substantially ellipsoidal with its axis concentric with the central line of the post 60 13, while in Fig. 4 the knob 20 is shown to be cylindrical. In the one case it fits in seats between the ribs or jaws 16 on the members 6 and 7 and in the other between the ribs or jaws 17 on the members 18 and 19. 65

In this present construction, the top of the lamp can be tipped forward or back so that the beam of light may be projected at any desired angle. When the axis of revolution passes through the center of gravity of the lamp, the lamp has little tendency to swing out of the desired position and a grip of the clamping members sufficiently strong to hold the lamp in place on the support 4 will also prevent the knob from turning between the jaws that position it. The seats on the clamping members prevent the knobs from turning on more than one axis. 75

I claim:

1. In a lamp mounting, the combination 80 of a pair of clamping members and a lamp having a projecting post and a knob on the end of the post of larger diameter than the post, said clamping members having seats to receive and permit rotation of the knob which is bounded by any surface of revolution other than a sphere, the seats extending around the knob to engage its sides and preventing the knob from turning on more than one axis, and a bolt to draw the clamping 85 members against the knob. 90

2. In a lamp mounting, the combination 95 of a pair of clamping members and a lamp having an ellipsoidal knob, said clamping members having seats to receive and permit rotation of the knob, the knob and seats being so formed as to prevent the knob from turning on more than one axis, and means to secure the clamping members to a support.

CHARLES E. GODLEY.
